UNITED STATES PATENT OFFICE

158,200

SPOTLIGHT

Joseph Kliegl, Queens Village, N. Y.

Application March 13, 1948, Serial No. 145,087

Term of patent 14 years

(Cl. D48—20)

To all whom it may concern:

Be it known that I, Joseph Kliegl, a citizen of the United States of America and resident of Queens Village, in the county of Queens and State of New York, have invented a new, original, and ornamental Design for Spotlight, of which the following is a specification, reference being had to the accompanying drawings, forming a part thereof, wherein:

Fig. 1 is a front elevational view of a spotlight, showing my new design;

Fig. 2 is a side elevational view thereof, omitting the lower portion of the stand;

Fig. 3 is a rear elevational view with the stand partly broken away; and

Fig. 4 is a view in perspective of the entire spotlight and its stand.

I claim:

The ornamental design for a spotlight, substantially as shown and described.

JOSEPH KLEGL.
